UNITED STATES PATENT OFFICE.

WILLIAM E. SLEIGHT, OF MILWAUKEE, WISCONSIN, ASSIGNOR TO THE UNITED STATES SWING TREADLE COMPANY, OF SAME PLACE.

SWINGING TREADLE.

SPECIFICATION forming part of Letters Patent No. 494,747, dated April 4, 1893.

Application filed December 18, 1891. Serial No. 415,466. (No model.)

To all whom it may concern:

Be it known that I, WILLIAM E. SLEIGHT, a citizen of the United States, and a resident of Milwaukee, in the county of Milwaukee and State of Wisconsin, have invented certain new and useful Improvements in Swinging-Treadles; and I do hereby declare that the following is a full, clear, and exact description thereof.

10 My invention relates to certain new and useful improvements in "swinging treadles" for foot power machines and consists in the matters hereinafter described and pointed out in the appended claims.

15 In the accompanying drawings illustrating my invention:—Figure 1. is a front elevation showing parts in section, of a device constructed in accordance with my invention.

20 Fig. 2. is a vertical sectional view of the same taken on line 2—2 of Fig. 1. Fig. 3. is a detail sectional view of one of the parts, taken on line 3—3 of Fig. 1. Fig. 4. is another detail sectional view of said part taken on line 4—4 of Fig. 1. Fig. 5. is another detail sectional view taken on line 5—5 of Fig. 1. Fig. 6. is a detail view of another of the parts taken on line 6—6 of Fig. 1. Fig. 7. is another detail view of one of the parts. Fig. 8. is a horizontal sectional view taken on line 8—8 of Fig. 2.

30 In said drawings:—A represents the table or top of the machine, B B the legs, C fly wheel and D the connecting rod or pitman which transmits motion from the treadle to said fly wheel.

35 E is a rock arm secured at one end to the lower end of the connecting rod or pitman as at d and at its other end provided with a suitable clamp E' for engaging with a sleeve F which is revolvably supported in the lower portion of the machine frame. This clamp E' is conveniently made in the form of a split ring adapted to grip the sleeve F and drawn together by means of a bolt e. As an additional 40 means for securing said clamp upon the sleeve F, a set screw e' is provided which firmly engages with the surface of said sleeve and effectually prevents said clamp from slipping thereon. The sleeve F is conveniently 45 supported upon a rod G supported in the lower part of the frame of the machine in any suit-

able or desired manner, as by the hangers or brackets H H secured adjustably to the frame by bolts h passed through the frame and engaged with slots h' in said hangers or brackets. Upon the rod G are provided suitable 55 conical bearing pieces G' G' adjustable lengthwise of said rod and held in their adjusted positions by set screws g g, said conical pieces being arranged to engage with correspondingly recessed bearing surfaces f f formed in the opposite ends of the sleeve F. The rod G is conveniently screw threaded at its ends and secured to the hangers or brackets H H by nuts g' g' as shown in the drawings. Arms 60 F' F' project from the sleeve F and are connected by means of links F' F' with the hanger of the treadle.

The hanger J by which the treadle is suspended from the top or the frame of the machine, comprises a lower portion J' bifurcated as shown and an upper portion K adjustably secured together in any suitable manner, as by means of the construction illustrated in the drawings in which an upwardly projecting arm j is provided upon the upper end of the lower section J', said arm being provided with a longitudinal channel or groove j' within which a downwardly projecting arm k on the upper part K is engaged, 70 and a bolt k' is passed through said arm k and a slot j' in the arm j so as to retain the upper and lower portions of the hanger in their adjusted positions. At the lower end of the hanger, between the two arms J' J', is 75 secured the foot piece or treadle I, said treadle being provided with upturned ears i i upon its opposite sides which ears are provided with grooves i' i' upon their outer sides in which the lower ends of the arms J' J' rest 80 and are secured by bolts i' i' so as to hold the treadle firmly in position between said arms. The upper end of the section K of the hanger is provided with hooks K' K' arranged to engage with a transverse rod L secured to the 85 lower side of the table or to the frame of the machine in any suitable manner.

In the particular form of construction illustrated in the drawings, this rod L is secured in bearings m m in the lower ends of hanger 90 blocks M. M. preferably secured to the top A by means of screw threaded shanks m' m'

made integral with said blocks and turned into the wood of the top. The rod L is prevented from moving longitudinally within the bearings m m by means of keys or cotters m².

5 m², passed through the rod L upon opposite sides of the hanger blocks M M. The upper end of the part K is retained in its engagement with the rod L by means of a screw K² passed through said part K and arranged to engage with the said rod below the center thereof so as to prevent the hooks K' K' from being lifted off from said rod L, while at the same time affording means for readily removing the hanger from said rod.

15 By the described arrangement of the devices for securing the suspension device or hanger to the machine, I am enabled to place the hanger blocks M M. in any convenient position and the location of said parts may 20 be varied to adapt the device for use in connection with any desired form of frame, and the suspension device or hanger may be secured to the transverse rod L at any point which is found most convenient.

25 By the vertically adjustable construction of the suspension device or hanger, I am enabled to lengthen or shorten said hanger so as to adapt it for use in connection with machines of various heights.

30 A further advantage is gained by the adjustable arrangement of the sleeve upon the rod G, from the fact that by this construction, I am enabled to shift the treadle to one side or the other as may be required by the peculiarities of construction of the various forms 35 of machine frames. So also by the adjustable arrangement of the hanger plates or brackets H H the height of the treadle above the floor may be varied to suit the convenience 40 of the user.

A still further advantage is gained by the described construction of the arm E with its connections with the sleeve F, inasmuch as by this construction the angle of said arm 45 may be varied to adapt it for connection with the pitman and fly wheel of different styles of machines.

A further adjustment of the rock arm E may be effected by means of the holes d d in 50 its free end, so as to adapt it for use upon fly wheels whose cranks have different lengths of throw without increasing or decreasing the necessary amount of movement of the treadle.

By my improvements therefore, I am en-

abled to provide for the adjustment of the 55 treadle mechanism at any point where adjustment may be necessary in order to adapt the treadle for use upon any desired form of foot power machine.

Having thus described my invention, what 60 I claim as new, and desire to secure by Letters Patent of the United States, is—

1. The combination with the frame of a foot power machine, of a swinging treadle comprising a hanger or suspension device, a foot 65 piece engaged with the lower end of said hanger, hanger blocks engaged with the lower side of the top of the machine a transverse rod mounted on said hanger block and hooks upon the upper end of said hanger adapted 70 for detachable engagement with said rod; substantially as described.

2. The combination with the foot piece and the suspension device of a swinging treadle, of suitable hanger blocks provided with integral screw threaded shanks adapted for engagement with the table or top of the machine a transverse rod or bar adjustably engaged 75 with bearings in said hanger blocks, hooks upon the upper end of the suspension device 80 adapted for engagement with said rod or bar, and a screw passed through the upper end of said suspension device and adapted to engage with the said rod or bar, substantially as and for the purposes described. 85

3. The combination with the swinging hanger and the foot piece of a swinging treadle of a transverse rod adjustably secured to the lower portion of the machine frame, conical bearing blocks adjustably secured upon said 90 rod and a sleeve provided with correspondingly shaped bearing surfaces in its opposite ends adapted for engagement with said conical bearing blocks said sleeve being provided with integral rock arms adapted for operative 95 engagement with the swinging hanger, and a collar adjustably engaged with the said sleeve and having an integral arm adapted for adjustable engagement with the operating portions of the machine, substantially as set forth. 100

In testimony that I claim the foregoing I have hereunto set my hand, at Milwaukee, in the county of Milwaukee and State of Wisconsin, in the presence of two witnesses

WILLIAM E. SLEIGHT.

Witnesses:
